DES 11952

No. 11,952

August 17, 1880

UNITED STATES PATENT OFFICE.

JAMES DWYER, OF DETROIT, MICHIGAN, ASSIGNOR TO DETROIT STOVE WORKS.

DESIGN FOR A STOVE-URN.

SPECIFICATION forming part of Design No. 11,952, dated August 17, 1880.

Application filed July 2, 1878. Term of patent 7 years.

To all whom it may concern:

Be it known that I, JAMES DWYER, of Detroit, in the county of Wayne and State of Michigan, have originated and designed a Top Ornament for Stove-Urns, of which the following is a full, clear, and exact description, reference being had to the accompanying photographic illustration, making part of this specification.

10 A represents the body of the urn, mounted on a cup-shaped base, B, which may be nickled and polished. An open bracket standard, C, springs from each side in the ornamental design represented.

15 D is a spherical mirror, hung in its horizontal axis between the standards C C by the

trunnions a a, whose pointed polygonal heads are nickled and polished.

To the face of the urn is secured a curved shield, b, having a raised scroll border, flat on the surface, nickled, and polished, with the raised and polished letters "D. S. W." on a pebbled ground. Below the shield is a sunken panel, c, with a scroll border and inclosed ornament of the configuration shown. 25

What I claim is—

A stove-urn of the design herein shown and described, provided with a spherical mirror, substantially as set forth and shown.

Witnesses: JAMES DWYER.
W. H. SHAW,
JAS. WEST.
